COMBINED METALLIC AND FABRIC AWNING STRUCTURE

Isidore Peter Smith, Maumee, Ohio, assignor to
The Hettrick Manufacturing Company, Toledo,
Ohio, a corporation of Ohio

Application December 27, 1950, Serial No. 202,853

2 Claims. (Cl. 160—22)

1

This invention relates to awnings, and an object is to produce a new and improved awning which can be adjusted to suit different weather conditions and can serve as a permanent installation if desired, so that instead of removing the awning during the winter period, a flexible portion or shade thereof can be readily and conveniently concealed and protected in a position beneath a permanent rigid portion of the awning, or, if desired, the flexible portion can be removed and stored.

Another object is to produce an awning which has a rigid section and a flexible fabric section or shade, which can be moved either to a protected position beneath the rigid awning section or to a selected outer position.

A still further object is to produce a simple and efficient awning unit having the new and improved features of construction and arrangement hereinafter more fully described.

By way of illustration but not of limitation, an embodiment of the invention is shown in the accompanying drawings, in which

Figure 1 is a front perspective view of the awning in position of use upon a window frame and showing by broken lines the flexible curtain extended to its outermost position of use;

Figure 2 is an enlarged fragmentary side elevation showing the mounting for the flexible awning section or shade beneath the outer portion of the rigid awning section;

Figure 3 is a transverse broken sectional view substantially on the line 3—3 of Figure 2; and

Figure 4 is a transverse section on the line 4—4 of Figure 3.

The illustrated embodiment of the invention comprises a building structure B having a window opening surrounded by a frame F and within the frame is shown the usual double sash window W. On the frame F near the upper portion thereof and on each side is a bracket 10 secured in any suitable manner as by screws 11 to the frame. The bracket 10 is formed with three arms 10a, 10b, and 10c, the arms terminating in scrolls 12 arranged substantially equi-distantly from each other. Bridging the space between the brackets 10 is a sheet metal plate 13 such for example, as galvanized or painted sheet steel, which is secured to the several bracket arms by bolt and nut assemblies 15a.

The upper edge portion of the plate 13 is turned down as indicated at 14 to abut against the cross member of the window frame F to which it may be fastened by screws or the like, if desired. The plate 13 is uniformly corrugated as indicated at 15, these corrugations being relatively wide and

2

extend from side to side and serve to prevent rain from running down the plate to the lower edge thereof. The front edge portion 16 of the plate is curled downwardly. Spaced rearwardly from the free or downturned edge 16 of the plate 15 and retained by the bolt and nut assembly 15a connecting the plate to the bracket arm 10c, is a fastener 17 of the conventional roller shade form, the inner end of which is bent to lie flatly against the under side of the plate 13. The body of the fastener 17 extends at substantially right angles to the plate and the free end is formed with a rearwardly inclined notch 18. On the opposite side is a similar bracket 17a which has a bearing hole 19 instead of the notch 18. Into the aperture 19 extends, for free rotation therein, the round projecting end of a rod 20 on which is mounted a hollow cylindrical shade roller 21. From the opposite end of the roller 21 extends the flattened end 22 of the rod 20, which is rectangular in cross section to fit the notch 18 to hold it against rotation.

Shade rollers 21 are well known in the art and embody a helical spring 21a surrounding the rod 20 to which one end is fixed, the other end being connected to the walls of the roller. When the roller is rotated in one direction, the spring is wound up to place it under tension, suitable pivoted tensioned pawls 21b being employed as a part of the assembly so that by a slight outward pull, the pawls are released to enable the spring to rotate the roller in the opposite direction, thereby to wind the shade about the roller. Shade rollers of this character are so well known in the art that further description and illustration thereof are not considered necessary. Suffice it to say that connected at one end to the exterior of the roller 21 is an awning shade 23 of any suitable flexible fabric material, such as canvas. Thus it will be manifest that the awning section or shade 23 can be wound upon the roller 21 and disposed almost entirely beneath the metallic awning section 15 when desired, thus protecting it from the weather.

Near the end of the awning shade 23 is a transverse pocket to receive the central portion of a U-shaped bracket 24 having depending arms, the lower ends of which are flattened and bent inwardly as shown at 25, these end portions being apertured to engage a vertically disposed support rod 26, which is attached to the lower portion of the frame F and offset therefrom a sufficient distance to afford free swinging and sliding movement of the bracket arms. A flap 27 of the awning shade extends beyond the bracket 24 and is scalloped for decorative purposes.

From the above description, it will be manifest that in normal use, the fabric awning shade may be swung or drawn outwardly to the broken line position shown in Figure 1, by merely pulling the bracket 24 outwardly and allowing the pawls 21b of the shade roller 21 to catch and retain the awning in that position. The weight of the metallic bracket 24 is sufficient to hold the awning shade with the desired tautness. If any intermediate position between the fully extended position and the outer end of the corrugated plate 15, is desired, this may be accomplished as will be readily understood, since the shade roller 21 can be caught in any selected position. On the other hand, on cloudy days when the full protection of the awning is not needed or during the winter months, the awning shade can be swung to its fully raised position so that the major portion wound upon the shade roller is protected from the elements. In the latter position, the corrugated metal awning section 15 affords some degree of protection for the window and also affords an attractive decorative addition.

In the event it is desired to remove or replace the canvas awning shade, this can be readily achieved by removing the bracket rods 26 from the window frame and detaching the roller shade from the bracket 17 in the usual manner as will be readily understood. This greatly simplifies the work of installation as well as replacement of the canvas awning portion.

It is to be understood that numerous changes in details of construction, arrangement and operation may be effected without departing from the spirit of the invention especially as defined in the appended claims.

What I claim is:

1. An awning structure comprising a metallic

awning section, brackets for opposite sides of the awning section for securing same to a building structure, a spring wound shade roller, a strip of flexible fabric awning connected at one edge to said roller, brackets for said roller connected respectively to the under side of said metallic awning near the outer edge portion thereof, a pair of bracket arms connected to the outer edge portion of said flexible fabric awning, and mountings for the free ends of said arms pivotally supporting said arms to enable the flexible fabric awning section to be unwound from or upon said roller.

2. An awning structure comprising a metallic awning section, brackets for opposite sides of the awning section for securing same to a building structure, a spring wound shade roller, a strip of flexible fabric awning connected at one edge to said roller, brackets for said roller connected respectively to the under side of said metallic awning near the outer edge portion thereof, a U-shaped bracket arm, means for connecting the transverse portion of the U-shaped bracket arm to the outer end portion of said flexible awning portion, and means adapted to be connected to a building structure for pivotally supporting the free ends of said U-shaped bracket.
